UNITED STATES PATENT OFFICE.

FREDERICK MANKEY, OF WILLIAMSPORT, PENNSYLVANIA.

DESIGN FOR A PANEL.

SPECIFICATION forming part of Design No. 17,183, dated March 15, 1887.

Application filed December 30, 1886. Serial No. 223,053. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photographs, forming part hereof.

A is a rectangular elevation having inclined upper edges. Parallel to the sides of said elevation A are rounded beads B, C, D, and E. Parallel to the beads B D are elevations G H, and parallel to the beads C E are elevations I J. Outside of and parallel to the elevations I J are beads K L. Outside and parallel to the elevations G H are beads M N. At each corner of the design is a rectangular elevation, O, four smaller rectangular elevations, F P Q R, and four short rounded beads, S T 20 U V. Between all the several elevations and beads named appear channels.

Figure 2 shows my design with the elevations A G H and beads B D and M N of Fig. 1 elongated. Fig. 3 shows my design in conjunction with additional elevations and channels.

Upon the upper surfaces of the elevations and beads T, K, I, V, C, E, J, and L may appear a different grain-marking from that which appears upon the surfaces of the elevations 30 and beads, at right angles to said elevations and beads.

I claim—

1. The design for a panel, substantially as herein shown and described, which consists in 35 the rectangular elevations A G O I H J F P Q R and beads B C D E S T U V K L M N, and intermediate channels.

2. The design for a panel, substantially as herein shown and described, which consists in 40 the rectangular elevations A G O I H J F P Q R and beads B C D E S T U V K L M N, and intermediate channels, a different grain-marking appearing upon the upper surfaces of the elevations and beads T, K, I, V, C, E, J, and 45 L from that which appears upon the surfaces of the remaining elevations and beads.

FREDERICK MANKEY.
